Des. 231,379
Patented Apr. 16, 1974

231,379

SHOE STILT

Earl C. Fields, 3660 Donegal Drive,
Cincinnati, Ohio 45236

Filed Apr. 24, 1972, Ser. No. 247,242

Term of patent 14 years

Int. Cl. D21—01

U.S. Cl. D34—14 E

FIG. 1 is a perspective view of a shoe stilt showing my new design;

FIG. 2 is a left end elevational view on a reduced scale;

FIG. 3 is a front elevational view;

FIG. 4 is a right end elevational view;

FIG. 5 is a bottom plan view; and

FIG. 6 is a top plan view.

The attaching straps have been omitted from FIGS. 2 to 6 for convenience of illustration.

I claim:

The ornamental design for a shoe stilt, as shown and described.
